THOMAS M. FINLEY, OF ST. LOUIS, MISSOURI

FLYING MACHINE

Application filed April 30, 1928. Serial No. 273,998.

The invention relates to improvements in flying machines.

The primary object of the invention is to improve the construction of flying machines 5 of the lighter than air cigar shaped type by eliminating head resistance and vacuum resistance and to replace the head resistance ordinarily encountered by flying machines of this type with a vacuum suck at the front end

10 and a siphon vacuum eliminating effect at the rear end.

Large lighter than air dirigible machines of the present type have two main resistances to which may be attributed their lack of successful or completely satisfactory operation, especially their failure to attain high speeds 15 and the difficulties encountered in their control.

What is meant by head resistance is the air 20 that banks at the front of the machine's body in resistance to flight. The body, being necessarily very thick, naturally, in action will collect tremendous volumes of air, which will bank at the front end and which creates 25 great resistance and causes the machine to be slow. Further, its resistance, in opposition to the propelling power, throws an enormous strain on the framework of the body of the machine. It also causes the body of the machine 30 to pivot at the front or contact end which gives an inefficient action to the means of control making the machine very slow in its movement under the operation of its controlling means.

35 This heavy bank of air packed at the contact end of the machine causes a swift flow of air back over the shoulders of the machine, and at that point the air leaves the machine's body, flying outwardly away from the body

40 of the machine and creating a partial vacuum from that point on to the rear end of the body. This partial vacuum has a strong suck effect upon the machine's body, in direct opposition to its forward progress. Therefore, we find

45 in this described action of the air two tremendous resistances to flight, to wit, head resistance by virtue of the air pack from the shoulders forward, and suck resistance by virtue of the vacuum from the shoulders rearward.

The present invention is designed to obviate all of the foregoing disadvantages by eliminating the head pack and by transferring the vacuum suck from the back of the machine to the front thereof, and thereby 55 convert what has heretofore been an obstacle to the forward progress of the machine into a means of assisting the forward movement or flight of the machine.

Another object of the invention is to eliminate the stream-line evil found in all cigar-shaped or stream-line shaped machines. The stream-line is used in the regulation type machine in an attempt to reduce the evil of the vacuum suck at the rear of the machine's 60 body, and doubtless does reduce it, but by no means eliminates it and such stream-line reduces the machine's gas capacity and thereby increases the ratio of its body weight to its 65 gas contents.

Another object of the invention is to increase the strength of the body of the machine and reduce the weight thereof and provide a body of the cigar-shaped type having greater 70 strength and less weight than those now in use.

With these and other objects in view, the invention consists in the construction and novel combination and arrangement of parts hereinafter fully described, illustrated in the 75 accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:—

Figure 1 is a front elevation of a flying 80 machine embodying the improvements of the present invention.

Fig. 2 is a plan view of the same.

Fig. 3 is a horizontal sectional view.

In the accompanying drawing in which 90 is illustrated the preferred embodiment of the invention, the flying machine comprises in its construction a body 1 provided with a centrally arranged vertical elongated tunnel 2 having a substantially flaring mouth or en- 100

trance and extending entirely through the body 1 from the front end to the rear end thereof. Although the tunnel is shown vertically elongated it may be elongated horizontally with substantially the same results so far as the movement of the air is concerned, so long as the body of the machine is made to conform correctly to the form of the invention illustrated in the accompanying drawings.

10 The body 1 is composed of inner and outer walls 3 and 4 connected at their ends with each other as clearly illustrated in Fig. 3 of the drawings, the inner wall defining the vertical elongated tunnel and the outer wall the exterior of the body of the machine. The intervening space 5 between the inner and outer walls constitutes the gas chamber and will in practice contain the supporting framework and as any desired construction of 20 supporting framework may be employed, illustration thereof in the present application is deemed unnecessary. The space 5 at the sides and bottom of the body between the inner and outer walls will permit of a framework composed of substantially vertical side frames and approximately horizontal top and bottom frames of any suitable truss formation and the arrangement will result in a lighter and stronger framework 30 formation than the framework of the ordinary flying machine of the cigar-shaped type.

The flaring mouth or entrance of the vertical elongated tunnel forms a front or outer shoulder 6, an inner or rear shoulder 7 and an 35 intermediate longitudinal connecting portion 8 extending from the inner edge of the outer shoulder to the outer edge of the inner shoulder. The flaring mouth or entrance is rounded slightly at 9 at the juncture of the outer shoulder and the intermediate longitudinal connecting portion 8 to present a convex exterior surface at the mouth or entrance and the said mouth or entrance is curved at 10 at the juncture of the longitudinal portion 8 and the inner shoulder 7 to present an exterior 45 concave surface at the mouth or entrance. The intermediate longitudinal connecting portion 8 is straight in longitudinal section and in parallelism with the adjacent portion 50 of the outer wall 4 of the body. The inner and outer shoulders 6 and 7 extend inwardly and rearwardly at an angle or inclination and recede from the straight lines $a b$ indicating the direct path of the air drawn into the mouth or entrance of the tunnel by front propellers 55 11. These front and rear shoulders by receding from the line $a b$ form suction pockets to create the suction hereinafter fully explained for assisting the forward movement or flight 60 of the body. The front or outer shoulder 6 is arranged at substantially an obtuse angle to the longitudinal connecting portion 8 to provide a flaring end to the mouth and the inner or rear shoulder extends inwardly transversely to form the pronounced pocket.

The body is equipped with a pair of front propellers 11 located at the upper and lower portions of the tunnel at the front thereof at the inner reduced end of the substantially flaring mouth or entrance and it has a pair of upper and lower rear propellers 12 located within the tunnel at the rear portion of the body, but any desired number of pairs of propellers may, of course, be provided and arranged similar to the front and rear propellers. The vertical distance between the top and bottom of the vertical elongated tunnel is greater than or in excess of the combined diameters of the propellers 11 to provide an expansion space for the air to prevent the air from packing in the tunnel and weighting the machine at the rear end thereof and interfering with the forward progress of the machine. This result is effected by providing the said expansion space between the upper and lower propellers which operate in close proximity to the walls of the tunnel at the top and bottom thereof, the curvature of the walls at the top and bottom being concentric with the circle in which the tips of the blades 90 of the propellers move.

The vertical elongated tunnel is the means employed to transfer the displaced air from the contact end of the machine and cause the said displaced air to move through the body 95 of the machine and out at the rear end thereof. The forward propellers draw the air from the front of the body of the machine into the tunnel, and in doing so, they draw the air around the shoulders 6 and 7 of the front 100 or contact end of the machine, thereby forming vacuums ahead of the shoulders.

The propellers being stationed in rear of the shoulders will draw the air in a straight line as indicated by the dotted lines $a b$ in Fig. 3 of the drawings. The air lines occur at the extreme inner edges of the shoulders and sucks out the air from in front of the shoulders, thereby creating a forwardly drawing vacuum. This vacuum effect occurs 105 at both of the shoulders 6 and 7 which form a stepped or corrugated surface from the outer end of the mouth or entrance to the front propellers which are located at the front end of the tunnel proper as clearly illustrated 110 in Fig. 3 of the drawings.

The reason for two such shoulders is that in case the machine in action should be opposed by a wind so violent that it should overcome the power of the propellers sufficiently to reach the outer or front contact shoulder 6 and thereby destroy or materially reduce the vacuum effect there, it would then slip inwardly and backwardly around the inner or second shoulder 7 and still produce a power vacuum ahead of the second shoulder 7 which would be of great assistance to the machine under these adverse conditions. The air passing through the tunnel not only produces a vacuum effect at the front end of the 115 120 125 130

body, but also produces a siphon effect at the rear end of the body.

The reverse siphon effect at the rear end of the body is of great importance and benefit, first, because it makes it possible to shorten very materially the slope or taper of the machine at the rear end over what is considered necessary with the stream-line of the ordinary flying machine of the cigar-shaped type, 10 and thereby gives much larger gas space for a given length over that of the ordinary stream-line bodies.

This is caused by virtue of the fact that the siphon moving body of air expelled at the 15 rear of the tunnel draws the air from around the body of the machine over the comparatively short slope or tapered portion 13 to the tunnel air, thereby effectively preventing a vacuum in the immediate wake of the 20 machine and at the same time obviating the necessity of a long tapering gas space reducing stream-line, which has a vacuum of great proportions. The siphon effect at the rear is no less important to successful flight than is 25 the vacuum effect at the contact end and the combined effect of the two make a powerful machine, compact in size, strong of body, swift in flight and easy in control because of the fact that such a machine will pivot at its 30 center rather than at the contact end as is the case with all cigar or stream-line shapes.

The reason for a transversely or vertical elongated tunnel is that experiments have shown that a round tunnel which is filled 35 with the propeller gives no room for the expansion of the air behind the propeller, and this expansion of air after leaving the propeller is natural and if prevented by the walls of the tunnel will cause high frictional resistance along those walls. This in turn, holds the air back and the further along the walls of the tunnel it goes, the slower its action. This soon creates an air pack, which 40 grows heavier and heavier the further it progresses along the walls, until it has created a tremendous weight at the rear end of the machine, adding to the weight of the whole machine and cutting down the power of buoyancy of the machine.

If the tunnel be enlarged in all directions, 50 that is, if a tunnel circular in cross section of materially greater diameter than the propeller be employed, then the current of air from the propeller moving swiftly through the center of the tunnel will not reach the outer walls of the tunnel and will draw the air away from the outer walls leaving in place thereof a vacuum and this vacuum makes the machine slow. Besides this effect, the propeller must 55 be long enough so that the ends of its blades may extend close to the tunnel walls immediately in rear of the shoulders at the stepped contact end of the body; otherwise, they will not create the vacuum there. Therefore, the 60 reason for the vertically elongated tunnel

with two propellers spaced apart so as to leave room between them is to take care of the natural expansion of the air, and at the same time create the vacuum at the front of the machine by virtue of the propellers being properly located with relation to the shoulders thereof of the corrugated or stepped contact end of the body.

The body is designed to be equipped with a suitable cabin 14 which is preferably arranged at the bottom of the body and which preferably extends partly within and partly exterior of the body, but a cabin or cabins of any preferred construction may be employed as will be readily understood.

What is claimed is:—

1. A flying machine body of the cigar-shaped type provided with a longitudinal tunnel and having propellers operating at opposite walls thereof, said tunnel being elongated cross sectionally in one direction to space the said opposite walls a distance greater than the combined diameters of the propellers to provide a central air expansion space between the propellers to prevent air 90 from packing in the tunnel.

2. A flying machine body of the cigar-shaped type provided with a vertically elongated tunnel and upper and lower propellers operating in the tunnel adjacent the top and bottom walls thereof, the vertical distance or height of the tunnel being greater than the combined diameters of the propellers to provide an air expansion space to prevent the air 95 from packing in the tunnel and weighting the body at the rear end thereof.

3. A flying machine body having a longitudinal tunnel provided with opposite transversely curved concave walls and substantially straight connecting walls, and propellers operating in the tunnel adjacent the curved walls, the said tunnel being elongated cross sectionally in one direction to space the curved walls a distance in excess of the combined diameters of the propellers to provide 105 an air expansion space to prevent the air from packing in the tunnel.

4. A flying machine body having a longitudinal tunnel provided at the top and bottom with transversely curved walls and having straight vertical side walls and elongated vertically, and upper and lower propellers operating in the tunnel adjacent the curved walls, the vertical distance or height of the tunnel being in excess of the combined diameters of the propellers to provide an air expansion space to prevent the air from packing in the tunnel and weighting the rear end of the body.

5. A flying machine body of the cigar-shaped type provided with a longitudinal tunnel having top, bottom and side walls and provided with a funnel-shaped mouth of stepped formation forming shoulders and providing suction pockets, and propellers op-

erating in the tunnel in rear of the said shoulders for drawing the air in the tunnel to eliminate a front pack and to cause suction at the said pockets.

5. 6. A flying machine body of the cigar-shaped type having a relatively short tapered rear end and provided with a longitudinal tunnel having top, bottom and side walls elongated cross sectionally in one direction, said 10 tunnel having a mouth or entrance of step-like formation consisting of inner and outer shoulders, and an intermediate longitudinal connecting portion, the outer shoulder extending outwardly from the intermediate connecting portion and the inner shoulder extending inwardly therefrom, and propellers arranged in the tunnel in rear of the said shoulders and spaced apart by the said elongation of the tunnel to provide an air expansion space, said propellers being adapted to 20 draw the air into the tunnel to prevent a front pack and to produce vacuum sucks at the said shoulders.

7. A flying machine body of the cigar-shaped type provided with a longitudinal tunnel having a flaring entrance of step-like formation consisting of inner and outer shoulders and an intermediate longitudinal connecting portion, the outer shoulder being arranged at an obtuse angle to the longitudinal connecting portion and extending outwardly therefrom to form a flaring end portion, and the inner shoulder extending inwardly in a transverse direction from the longitudinal connecting portion to provide a pronounced pocket, and propellers operating in the tunnel in rear of the said shoulders.

8. A flying machine body of the cigar-shaped type provided with a longitudinal tunnel having a flaring entrance of step-like formation consisting of inner and outer shoulders and an intermediate longitudinal connecting portion, the outer shoulder being arranged at an obtuse angle to the longitudinal connecting portion and extending outwardly therefrom to form a flaring end portion, and the inner shoulder extending inwardly in a transverse direction from the longitudinal connecting portion to provide a pronounced pocket, and propellers operating in the tunnel in rear of the said shoulders, and located adjacent the upper and lower walls of the tunnel, the latter being vertically elongated and the vertical distance or height of the tunnel being in excess of the combined diameters of the propellers to provide an air expansion space to prevent the air from packing in the tunnel and weighting the rear end of the body.

60. 9. A flying machine body of the cigar-shaped type provided with a longitudinal tunnel having a mouth of step-like formation consisting of inner and outer shoulders and an intermediate longitudinal connecting portion, the outer shoulder being disposed at an

obtuse angle to the intermediate portion to provide a flaring end, and an inner shoulder extending inwardly transversely from the rear end of the intermediate portion to form a pronounced pocket, and upper and lower 70 propellers located in the tunnel in rear of the said shoulders and arranged adjacent the top and bottom walls thereof, the tunnel being vertically elongated and the vertical distance or height of the tunnel being in excess of the 75 combined diameters of the propellers to provide a central or intermediate air expansion space to prevent air from packing in the tunnel and weighting the rear end of the body.

In testimony whereof I affix my signature. 80
